UNITED STATES PATENT OFFICE.

EDWARD LLOYD PEASE, OF DARLINGTON, ENGLAND.

TUBULAR HEAT-INTERCHANGING APPARATUS.

1,312,045.

Specification of Letters Patent.

Patented Aug. 5, 1919.

Application filed October 14, 1915. Serial No. 55,814.

To all whom it may concern:

Be it known that I, EDWARD LLOYD PEASE, a subject of the King of Great Britain and Ireland, residing at Darlington, in the county 5 of Durham, England, have invented Improvements in Tubular Heat-Interchanging Apparatus, of which the following is a specification.

It is usual in radiators constructed for the 10 heating of rooms, shops and the like for the heating agent to be conveyed through a cast iron or wrought iron structure the walls of which form the direct medium for the transfer of heat from the heating agent within 15 to the air outside. Owing to this, the area of the surface exposed to the air is much less in proportion to the interior surface in contact with the heating agent than should be the case to provide an efficient transfer of 20 heat to the air, and further, the exterior surface of the radiator being at practically the same temperature as the internal heating agent, it is liable to become dangerously hot.

Now the present invention has reference to 25 an improved construction of heat interchanging apparatus or radiator wherein the portions of the apparatus which give off heat to the greatest extent to the surrounding air are in the form of metal strips that 30 are merely attached to that part of the structure which acts as the transmitter of heat from the heating agent and extend substantially the full height of such structure so as to form long upwardly extending continuous 35 air passages freely open at the sides so that air can gain ready access to all parts of apparatus. The number and dimensions of the strips can be increased to any desired extent in relation to the part of the structure that 40 acts as a transmitter of heat so that a large transfer of heat can take place from the heating agent to the surrounding air while the exposed surfaces of the radiator can be maintained at a moderate temperature.

45 Heat interchanging apparatus or radiators of the kind described can be constructed in various forms without departure from the essential feature of the invention.

Thus, according to one construction, connecting two separate and independent end headers placed vertically and provided with suitable inlet and outlet branches is a series 50 of horizontal brass or steel tubes on which are fixed a series of closely pitched thin metal strips of about the same length as the end headers and also vertical. These strips

are secured to the tubes by expanding the tubes into contact with them, or by brazing them to the tubes, or in both these ways, or by other ordinary means. The holes in the 60 strip through which the tubes extend may be flanged or not. Usually it will be found advantageous not to flange the holes. The heating agent, which may be steam or hot water, can pass up one header, then across 65 the connecting tubes and down the opposite header, transmitting in its passage, its heat through the tubes to the metal strips, which, owing to the great amount of surface which they expose to the air, are very efficient in 70 their heating effect.

It will be understood that the metal strips need only be made of a comparatively small width to insure that their outer edges shall be at a moderate temperature whatever may 75 be the temperature of the heating agent.

In the accompanying drawings, Figure 1 is a front elevation and Fig. 2 an end elevation of one specific construction of heat interchanging apparatus according to the invention adapted for use as a heat radiator. Fig. 3 shows in side elevation, part of the upper portion of the heat radiator with a modified construction of metal strips. Figs. 4 and 5 show in horizontal section, part of a 80 heating tube and some of the metal strip thereon, the two figures showing different arrangements of the strip to that shown in Figs. 1 and 2. Fig. 6 shows in plan part of a horizontal heating tube and some of the 85 metal strips thereon adjacent to a wall.

As shown in Figs. 1 and 2, *a* is a header having a single branch connection *b*, and *c* is a similar header but having two branch connections *d*, *e*. With the aid of cocks *f* and piping *g* the flow of heating fluid through the radiator can be controlled as usual. *h* are the horizontal tubes on which are secured by outward expansion of the tubes or in any other suitable way the vertical metal strips *i*. Such strips may have rounded ends as seen in Fig. 2, and be identical one with another. By this arrangement, all the tubes will be heated similarly and each strip will be heated approximately to 100 the same degree by the tubes to which it is fixed so that it will not act to transmit heat from one part of the structure to another.

Also, the vertical strips need not be separated from each other. Thus, as shown in 110 Fig. 3, two of them may be bent out of the same strip, producing at the top a rounded

bend *j* which has the advantage of offering a smooth instead of a serrated surface to the upper part of the radiator and in dividing the current of heated air rising from the 5 radiator laterally into separate currents.

Having described the general construction of the apparatus it is to be understood that the details can be varied. Thus, it is not essential that the metal strips *i* should be of 10 uniform width in the same radiator. For example, as indicated in horizontal section in Fig. 4 every alternate strip may, with advantage, be narrower than that on each side of it so that two wider strips will, at their 15 outer extremities, be separated by double the normal spacing width plus that left vacant by the absence of the intermediate strip in that part. By this means a valuable air passage is provided between each adjacent pair 20 of wider strips which is found to produce a much better radiation of heat from the plate to the air than is the case when the plates are all of the same width, the pitch of the plates being the same in the two cases. Also, 25 the edges of the wider strips will not be unduly hot and therefore will not be liable to cause injury to any one accidentally touching them by hand. In the same way strips *i* of unequal width may be arranged so that 30 the edges of all extend at one side to the same distance as shown in Fig. 6, this being an arrangement that is specially applicable where a radiator is to stand against or adjacent to a wall such as is illustrated at *s*. 35 Similarly, the feature of increased air passage in proportion to strip area can be obtained by fixing strips of the same width as in Fig. 1 in staggered relationship upon the tubes *h* as exemplified in Fig. 5 this being rendered possible by forming the tube 40 holes in a line nearer to one edge of the strip than the other.

Heat interchanging arrangements of the kind herein described can of course be used 45 in apparatus for the interchange of heat between fluid mediums of various kinds other than steam and air, as for instance steam and water, water and oil, or heated air or other gases and water or other liquid, the 50 hotter medium passing through the tubes or between the gills as may be desired.

What I claim is:—

1. Heat interchanging apparatus comprising a vertical metal structure through which 55 fluid can flow horizontally, means for effecting the supply of fluid laterally to one side of said structure, and means for effecting the withdrawal of fluid laterally from the opposite side of said structure so that said fluid 60 can flow horizontally through the structure in one direction only and can flow simultaneously through portions of the structure situated at different levels, and a series of flat upwardly extending metal strips fixed, at a 65 distance apart, to the exterior of said struc-

ture and each extending substantially the full height of the structure so that there is formed between each adjacent pair of strips, a single upwardly extending continuous passage freely open at the outer side and 70 through which a single stream of fluid can freely flow upwardly in contact with the structure and strips.

2. Heat interchanging apparatus comprising a metal structure having an inlet 75 for fluid at one side of said structure and an outlet for fluid at the opposite side thereof, said inlet and outlet extending substantially the full height of the structure so that the fluid can flow horizontally through it 80 in one direction only and simultaneously through its portions situated at different levels, and a series of upwardly extending flat metal strips fixed, at a distance apart, to the exterior of said structure and each extending substantially the full height of the structure 85 so as to form at each side of the structure a series of upwardly extending passages for external fluid, each of which passages extends uninterruptedly through 90 substantially the full height of the structure.

3. Heat interchanging apparatus comprising vertical inlet and outlet side headers, a series of horizontal tubes connecting said 95 headers and arranged at different heights with no two tubes at the same height, and through which fluid can flow simultaneously in the same horizontal direction from the one header to the other header, and a series of vertical flat metal strips each fixed to 100 all the tubes and forming between them vertical uninterrupted passages for flow therethrough of external fluid.

4. Heat interchanging apparatus comprising vertical inlet and outlet side headers, a series of horizontal tubes arranged with their axes in a single vertical plane and so connecting said headers that fluid can 105 flow through said tubes simultaneously 110 from the inlet to the outlet header, and a series of vertical flat metal strips spaced apart and each fixed to all the tubes.

5. Heat interchanging apparatus comprising vertical inlet and outlet side headers, a series of horizontal tubes arranged at 115 varying heights and connecting said headers and a series of vertical metal strips each fixed to all the tubes, one strip extending horizontally to a distance from the tubes 120 differing from that to which the edge of an adjacent strip extends in the same direction.

6. Heat interchanging apparatus comprising vertical inlet and outlet side headers, a series of horizontal tubes arranged at 125 varying heights and connecting said headers and a series of vertical metal strips each fixed to all the tubes, the edges of some of the strips being at one side of the apparatus, at a different distance from the tubes 130

than the edges of other strips, at the same side of the apparatus, so that the edges of the strips at the one side of the apparatus are in staggered relationship.

- 5 7. Heat interchanging apparatus comprising vertical side inlet and outlet headers, a series of horizontal tubes arranged at different heights and connecting said headers, and a series of closely pitched vertical metal strips of different width each fixed 10 on all of the tubes, a strip of one width being arranged between strips of another width.
8. Heat interchanging apparatus comprising vertical side inlet and outlet headers, horizontal tubes arranged at varying heights and connecting said headers and a series of closely pitched vertical metal strips of different widths each fixed to all of 15 the tubes, a strip of one width being arranged between strips of another width and the edges of all the strips extending at one side of the series of tubes to substantially 20 an equal distance.
- 25 9. Heat interchanging apparatus comprising vertical side inlet and outlet headers, a vertical series of horizontally ar-

ranged tubes connecting said headers and a series of vertically arranged strips of metal each fixed to all the tubes, the strip edges 30 extending to different distances at one side of the series of tubes so as to produce vertical spaces differing in width and offering a varying frictional resistance to flow of fluid through such spaces.

35 10. Heat interchanging apparatus comprising vertical side inlet and outlet headers, a vertical series of horizontally arranged tubes connecting said headers, and a series of vertically arranged closely 40 pitched metal strips of different widths each secured to all the tubes, a strip of one width being arranged between strips of another width and the edges of all the strips 45 extending at one side of the series of tubes to substantially an equal distance.

Signed at Newcastle-on-Tyne, England, this twenty-fourth day of September, 1915.

EDWARD LLOYD PEASE.
